UNITED STATES PATENT OFFICE.

EDWARD H. DIECKMANN, OF FLORISSANT, MISSOURI.

POWER UNIT.

Application filed January 24, 1924. Serial No. 688,267.

This invention relates to power units, and more particularly to portable power units, such as may be used for driving various types of domestic and farming implements found 5 on the ordinary farm.

The household equipment of the ordinary farm usually includes such machines as washing machines, churns, cream separators, feed grinders, and similar machinery for carrying 10 out the various semi-domestic operations which are ordinarily a part of the routine on a farm. Many of these machines are equipped for hand operation and it is desirable to have at hand some means for driving the same by 15 mechanical power. Since it would be too expensive to provide a separate power drive for each machine, a portable power unit arranged to be easily applied to the drive of any of these machines is a great convenience.

20 One of the objects of this invention is, therefore, to provide a power unit which is easily portable and which may be adapted to drive any of the above types of machines.

Another object is to provide such a unit 25 which may be adapted for operation with a minimum of alteration and in a short time.

Another object is to provide such a unit in which the mechanical arrangements are simple so that they may be handled by one 30 not especially skilled in mechanical arts.

Further objects will appear from the detail description taken in connection with the accompanying drawing, in which:

Figure 1 is a view in side elevation of a 35 device embodying this invention shown as applied to a washing machine;

Figure 2 is an end view of Figure 1; and Figure 3 is a section on line 3—3, Figure 1.

Referring to the accompanying drawing, 40 1 designates the body of a washing machine such as is ordinarily equipped with manual driving means. These means often take the form of a pulley or wheel 2 in the nature of a balance-wheel equipped with a handle 3 by means of which the wheel may be turned to operate the machine. In accordance with this invention a portable base or truck 4 is provided which may be equipped with running gear comprising wheels or casters 5 and 45 feet 6 to support the same when at rest and also with handles 7 by means of which the truck may be handled in moving the same from place to place. A motor, such as a gas or gasoline engine 8 may be mounted on one 50 end of the truck 4. This motor may be provided with a driving pulley 9 adapted to

receive a belt 10 which passes over a belt-pulley 11 adjustably mounted upon an upright arm or carrier 12. The arm 12 is pivoted at 13 on a bracket 14 and is provided with a side extension 15 adapted to engage a spring 16 mounted between the extension 15 and the bracket 14 and adapted to tension the arm 12 so as to provide a yielding tension in the belt 10. The arm 12 may 60 be provided with a stop 17 to limit its movement under the influence of the spring 16.

The pulley 11 may be adjustably mounted on the carrier 12 as shown in detail in Figure 3. The arm 12 is provided with a slot 18 within which a bolt 19 may slide. This bolt carries a sleeve 20 having an enlarged head or flange 21 adapted to bear against one side of the arm 12. The head of the bolt 19 or washer 24 thereon bears against one end of the sleeve 20 and the other end of said bolt is provided with a nut 22 having a manipulative handle 23 by means of which the sleeve 20 may be securely clamped to the arm 12 in any desired position along the slot 18, a 70 washer being preferably interposed between the nut 22 and the slotted arm 12. The outer surface of the sleeve 20 is adapted to provide a bearing for the pulley 11. Thus by loosening the nut 22, the bolt 19 may be slid to 75 any position along the slot 18 so as to raise or lower the pulley 11 and then securely clamped in adjusted position.

In using this device, the power unit may be brought to the machine which is to be 80 driven. The unit is brought up in such a position that the belt 10 will be properly aligned with the wheel or pulley 2 with which the machine to be driven is equipped. The truck is then moved so that the belt 10 will 85 come into engagement with the pulley 2 as shown in Figure 1. As the pulley is under yielding tension, the same can be adjusted to have a considerable arc of contact with the pulley 2 so as to provide an effective 90 drive. The pulley 11 being elevated with respect to the pulley 9, the upper strand of the belt 10 will take an inclined position, such that the belt may be brought into driving engagement by merely running the truck under 95 the pulley 2; this can readily be done due to the fact that not only can the pulley 9 be on the opposite end of the fly-wheel of the engine as shown, but in view of the fact that both pulleys as well as the belt can be 100 arranged on one side of the truck, this belt is positioned for such engagement by the 105 110

pulley or other element to be driven. At the same time, the spring 16 provides for a yielding tension on the belt so that a good driving engagement is attained.

It will be noted that this unit may be applied to any machine which is equipped with a wheel 2 suitable for use as a pulley whether intended for that purpose or not. The construction is simple and easily operable by any one, even though not skilled in the mechanical arts. When not in use, the unit may be simply moved aside and is always ready to be applied when needed. While the power unit is particularly applicable to the specific uses described, it will be understood that its application is general; it is further obvious that various changes may be made in details of construction without departing from the spirit of this invention; it is therefore, to be understood that this invention is not to be limited to the specific details shown and described.

Having thus described the invention, what is claimed is:

- 25 1. A portable power unit, comprising, a truck provided with running gear whereby it may be set adjacent a pulley equipped machine to be driven, a motor mounted on said truck and provided with a driving pulley, a carrier mounted on said truck and provided with a belt tightening pulley, and a belt passing over said pulleys and positioned to provide a driving face adapted to engage the machine pulley when the unit is set adjacent the machine in order to drive the same.
- 30 2. A portable power unit, comprising, a

truck provided with running gear whereby it may be set adjacent a pulley equipped machine to be driven, a motor mounted on said truck and provided with a driving pulley, a carrier mounted on said truck and provided with a belt tightening pulley spaced from and at a different level than said driving pulley, and an inclined belt passing over said pulleys and positioned to provide a driving face adapted to engage the machine pulley when the unit is set adjacent the machine in order to drive the same.

3. A portable power unit, comprising, a wheeled truck adapted to be moved about by hand, a motor thereon provided with a pulley, a hinged bracket spring tensioned on said truck, a belt tightening pulley adjustable along said bracket at a different level than said motor pulley, and an inclined belt on said pulleys tensioned thereby and positioned to engage a pulley to be driven.

4. A portable power unit, comprising, a wheeled hand truck, a motor mounted on the lower end thereof and having a pulley, a spring-tensioned bracket pivoted on the upper end of said truck and having an idler pulley adjustably mounted on the upper end thereof, and an inclined belt running on said pulleys at one side of said truck, whereby said belt may be placed in driving engagement with a driven pulley by moving said truck thereunder.

In testimony whereof I affix my signature this 12th day of January, 1924.

EDWARD H. DIECKMANN.
